[57] CLAIM

The ornamental design for a skateboard, as shown and described.

DESCRIPTION

FIG. 1 is a top perspective view of a skateboard showing our new design;

FIG. 2 is a bottom perspective view thereof;

FIG. 3 is a right side elevational view thereof shown on an enlarged scale;

FIG. 4 is a top plan view thereof;

FIG. 5 is a cross-sectional view thereof taken along line 5—5 of FIGS. 3 and 4;

FIG. 6 is a cross-sectional view thereof taken along line 6—6 of FIGS. 3 and 4;

FIG. 7 is a cross-sectional view thereof taken along line 7—7 of FIGS. 3 and 4;

FIG. 8 is a cross-sectional view thereof taken along line 8—8 of FIGS. 3 and 4;

FIG. 9 is a cross-sectional view thereof taken along line 9—9 of FIGS. 3 and 4;

FIG. 10 is a cross-sectional view thereof taken along line 10—10 of FIGS. 3 and 4;

FIG. 11 is a cross-sectional view thereof taken along line 11—11 of FIG. 4; and

FIG. 12 is a cross-sectional view thereof taken along line 12—12 of FIG. 4.

The skateboard truck and wheel members have been omitted from FIGS. 5 through 12 for ease of illustration.
